ALBERT SCHRAFFT, OF NEWARK, NEW JERSEY, ASSIGNOR TO TABOR SASH FIXTURE CO., OF NEWARK, NEW JERSEY, A CORPORATION OF NEW JERSEY.

PIVOTED WINDOW.

1,102,202.

Specification of Letters Patent. Patented June 30, 1914.

Application filed November 1, 1913. Serial No. 798,617.

To all whom it may concern:

Be it known that I, ALBERT SCHRAFFT, residing at Newark, county of Essex, State of New Jersey, have invented certain new and 5 useful Improvements in Pivoted Windows, of which the following is a full, clear, and exact description.

My invention relates generally to windows in which the sash can be slid up and down 10 for opening or closing the window in the usual manner, and which can also be turned on pivots so that access may be had to both sides of the sash from the inside of the building, and more particularly to the guide-bars 15 for such windows. As is well known to those skilled in the art, when windows of this class are being installed, serious binding of the guide-bars results if the window stops are not in proper spaced relation there- 20 to. These guide-bars are often made to stick or bind by the paint which is placed on the window parts after the stops have been secured in permanent position.

The general object of my device has been 25 to overcome this disadvantage and inconvenience, and I have accomplished this by providing a guide-bar having a narrow spacing ridge, which, when the window is first turned on its pivots breaks and is detached from the 30 guide-bar, thus leaving the required amount of clearance space.

Reference is to be had to the accompanying drawings forming part of this specification, in which like characters of reference in- 35 dicate like parts, throughout the several views, of which:

Figure 1 shows a front elevation of a window frame, to which my invention is applied. Fig. 2 is a sectional elevation of 40 the same taken on line 2—2 of Fig. 1. Fig. 3 is an enlarged fragmentary sectional view of the guide-bar with its ridge and is taken on line 3—3 of Fig. 1. Fig. 4 is an enlarged fragmentary perspective view of one of the 45 guide-bars of my window provided with a spacing ridge. Fig. 5 is an enlarged fragmentary sectional view taken on line 3—3 of Fig. 1 and shows a modification of my invention in which the spacing ridge is pro- 50 vided on the window stop. In the drawings, 5 represents the window casing which is of the usual construction, and 6 and 7 the upper and lower window sashes, respectively. These window sashes are pivoted at or near 55 their centers to the guide-bars 8 and are

slidable up and down in guideways provided in the window casing as usual. Each guide-bar 8, upon the surface which contacts with the window sash, is provided with an irregularly curved surface which co-acts with a 60 substantially similarly curved surface on the edge of the window sash, as is customary in window constructions of this type. Preferably, the face 9 of each guide-bar, adjacent to the window casing, is inclined somewhat 65 (see Fig. 3) so that its face 9 makes an angle with the face 15, which is less than a right angle, and is provided at the edge 10 with a thin longitudinally extending spacing ridge 11. The height of this ridge above the 70 surface 12 of the guide-bar is such as to give proper clearance space between the guide-bar and the stop 13 of the window.

In the modification shown in Fig. 5, I carry out my invention by providing a thin 75 longitudinally extending spacing ridge 11^a on the window stop 13^a, which is arranged to bear against the curved surface 12 of the guide-bar 9.

When windows provided with my guide-bars are installed, the window stop 13 or 13^a is placed up against the guide-bar 8 with the spacing ridge 11 or 11^a therebetween, whereupon the stop is secured in place in the usual manner. When the window sash is turned 85 upon its pivots, the guide-bar 8 will be given a lateral motion between the stops. The guide-bar will also be slightly oscillated around the corner 14 as a center, and as the face 9 is inclined, this oscillating motion will 90 cause the narrow ridge 11 or 11^a to be wedged in between the stop and guide-bar and to be thereby broken off and severed from the same. After this ridge is once broken away the guide-bars will always have 95 a predetermined amount of clearance equal to the height of the ridge before being broken off. It will be obvious that by providing these narrow ridges on the guide-bars, the stops may be set in uniform and spaced relation with the guide-bars, and thus obviate any binding of the same due to poor or care- 100 less workmanship in fitting the window sashes, or of binding caused by paint.

Having thus described my invention, what 105 I claim is:

1. The combination with a window frame provided with window stops and a pivotally mounted sash which clears said stops, of a 110 guide-bar capable of turning transversely

between said stops and bearing against said sash, and a spacing ridge between one of the edges of said guide-bar and one of said stops.

2. The combination with a window frame 5 provided with window stops and a pivotally mounted sash which clears said stops, of a guide-bar capable of turning transversely between said stops and bearing against said sash, said guide-bar being provided on one 10 of its edges which face said stops with a spacing ridge.

3. The combination with a window frame provided with window stops and a pivotally mounted sash which clears said stops, of a 15 guide-bar capable of turning transversely between said stops and bearing against said sash, said guide-bar being provided on one of its edges which face said stops with a spacing ridge, and having its face, which is 20 opposite the sash, inclined toward said spacing ridge.

4. The combination with a window frame provided with window stops and a pivotally

mounted sash which clears said stops, of a guide-bar capable of moving laterally and 25 turning transversely between said stops and bearing against said sash, said guide-bar being provided on one of its edges, which face said stops, with a spacing ridge.

5. The combination with a window frame 30 provided with window stops and a pivotally mounted sash which clears said stops, of a guide-bar capable of moving laterally and turning transversely between said stops and bearing against said sash, said guide-bar 35 being provided on one of its edges, which face said stops, with a spacing ridge, and having its face, which is opposite the sash, inclined toward said spacing ridge.

In testimony whereof, I have hereunto 40 signed my name in the presence of two subscribing witnesses.

ALBERT SCHRAFFT.
